Ben V. Zillman
Attorney.

UNITED STATES PATENT OFFICE.

EDWARD HOFFMAN, OF ST. LOUIS, MISSOURI.

RUBBER HEEL.

Application filed October 13, 1926. Serial No. 141,259.

My invention relates to improvements in rubber heels and the method of attaching the same, and has for its objects the simplification of the present practice in this art.

5 Among the objects of my invention are the production of heels of the kind described, which shall be speedily and economically attached to the shoe, without danger of accidentally becoming detached therefrom in the course of use, will make a job neat and attractive in appearance, shall be simple, and which shall be efficient and satisfactory for use wherever found applicable.

15 Many other objects and advantages of the construction herein shown and described, will be obvious to those skilled in the art to which this invention appertains, from the disclosures herein given, and to this end my invention consists in the novel arrangement, construction and combination of parts herein shown and described, and more particularly pointed out in the claim.

20 In the present practice of shoe-making, rubber heels are attached to shoes by driving tacks upwardly through the series of openings through the heel, these tacks entering the leather top lift, outer sole and inner sole, and then clinched down inside the shoe. When repairing, or replacing the rubber heels, these tacks must be pulled out, and the new tacks driven back into the same holes previously formed through the outer and inner soles. Obviously the new tacks will not hold as firmly as the original ones unless 25 of a larger size than the ones first driven in.

30 My invention has among its objects means whereby all of this tacking is done away with, and no new "tacks" need be handled when replacing the heels.

35 In the drawings, wherein like reference characters indicate like or corresponding parts throughout the views,

40 Figure I is a fragmentary portion of a shoe, showing a rubber heel and leather top lift affixed thereon;

45 Figure II is a top plan view of the leather top lift of my improved construction.

50 Figure III is a longitudinal cross-section through the rubber heel and leather top lift, the parts being shown in their attached relationship;

55 Figure IV is a dis-assembled view of these parts, showing a modified form;

60 Figure V is an elevation of an attaching pin;

65 Figure VI is an elevational perspective of the modified form of washer; and

70 Figure VII is a sectional detail of the pin and washer shown in Figure IV, after these elements are in final position.

75 In the drawings, wherein I have illustrated the preferred embodiments of my invention, there is shown a shoe having the usual or any preferred shape and size, indicated at S, the outer sole being indicated at 1. As is customary, a lift 2, preferably of leather, is affixed to the rear or heel portion of the outer sole, and a rubber heel R is positioned below the lift 2.

80 The lift 2 may be affixed to the outer sole by any desired or suitable means, as by tacks or the like, but prior to the affixing of the lift to the outer sole, a series of openings or apertures 3 are provided therethrough. There may be any number of these apertures, arranged in any suitable spacing, it being noted that there are less than half as many apertures required as compared with the apertures now provided in rubber heels.

85 Fastening means 4 are inserted through the apertures 3 of the lift, before attaching said lift permanently in place, these fastening means each comprising a shank portion having a head 5 at one end, and an annular groove 6 adjacent the other end, the last-mentioned end being preferably rounded as shown at 7. After insertion of these pins 4 into the apertures 3, from the top side of the lift, the lift is secured to the shoe.

90 When it is desired to use rubber heels having the usual type of washers 8 therein, the free end of the pins 4 must project downwardly below the lower surface of the lift 2, as shown in Figure III. Obviously the pins 4 will register with the apertures of the washers 8 of the heel, so that when the rubber heel and the lift are pressed together, the reduced end of the pins will snap past the washers and interlock therewith, the washers remaining in such position that

95 they will each encircle the reduced or neck portion of their co-operating pin. If desired, the washers 8 may be split or otherwise formed, so as to render them more resilient. Thus the heels will be retained in their attached position until it is desired to remove 100 or replace the heel. The replacing of the heel is extremely simple, inasmuch as all that it takes is that the old heel be snapped off and the new heel be snapped on.

In order that the heel may be worn down to the extreme limit it is preferable that the washers be placed near the top of the heel and in order to provide still further wearing qualities I have shown in Figures IV to VII inclusive, a type of heel R' wherein the washer 8' projects upwardly beyond the top surface of the heel, the pins 4 being shorter than that previously described, and in the present instance terminating within the plane of the lower surface of the lift 2.

These washers 8' are preferably hollow tubes, reduced at their ends and flared outwardly intermediate the ends as shown at 9, so that these washers may be firmly imbedded within the body of the rubber when forming the heel. These washers are preferably split as shown, so as to be expansible and self-contracting, so that when the pin 20 ends 7, enter the washers, the washers will be temporarily expanded, and then will snap back into shape to encircle the ball end of the pin. On account of the projection of the washers and the recessing of the free ends of the pins, the heels must be tightly pressed into place when assembling, and when released, the washers will be interlocked with the pins, and the heel will be retained tightly against the under surface of 30 the top lift 2, until forcibly released for replacement or a like purpose.

Thus it is seen that I have provided an article that is easy to make in practice, is economical, speedy, and neat. In addition, the wearing qualities of the heels are increased, for, in the modified form just described, the washers may be worn down flush with the top of the heel before it is necessary to replace the heel, the shape 40 of the washer being such as to interfere but

slightly with the cushioning effect of the rubber heel.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned, except as limited by the claim.

What I claim as new and desire to secure by Letters Patent is:

In combination, a leather lift adapted to be affixed to a shoe and provided with apertures extending therethrough, pins insertable through said apertures from the upper side before said lift is affixed to the shoe, said pins having a head end terminating within the apertures above the bottom surface of the lift, a rubber heel having expansible washers therein and projecting above the heel, said washers being reduced in radial cross-section toward both ends so as to securely anchor them against vertical movement in both directions, and the lower ends of said washers terminating above the tread surface of said heel, whereby when the heel is pressed against said lift, said washers will be received within said apertures of the lift to receive the heads of said pins, and thereby pull said heel up tightly against said lift, the major portion of the washers forming a part of the tread surface of the heel after a predetermined amount of wear of the latter, so that the entire heel can be worn down adjacent the washer without exposing the head of the pin to wear.

EDWARD HOFFMAN.
